Primary Examiner — Sheryl Lane*Assistant Examiner* — Samantha N Wood(74) *Attorney, Agent, or Firm* — Taft Stettinius & Hollister LLP(57) **CLAIM**

The ornamental design for a watch dial, as shown and described.

DESCRIPTION

FIG. 1 is a front elevational view of a watch dial showing my new design;

FIG. 2 is a back elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, bottom, right side perspective view thereof; and,

FIG. 8 is a back, bottom, left side perspective view thereof. The broken lines in the drawing figures form no part of the claimed design.

The solid black areas in the drawing figures are intended to show color.
